DISPENSING POWDER PUFF

Myrtle L. Harllee, Los Angeles, Calif.

Application May 5, 1942, Serial No. 441,789

1 Claim. (Cl. 15—131.1)

This invention relates to powder puffs and more particularly to dispensing powder puffs.

One of the primary objects of my invention is the provision of a dispensing powder puff embodying a highly practical, efficient, neat and durable closure member for its filling opening, which member also serves to provide a pocket into which the fingers of the user may be inserted for holding the puff during use and filling.

Another object is the provision, in such a dispensing powder puff, of means for efficiently distributing and regulating the dispensing of powder through the dispensing wall.

Another object is the provision of a device of this character which is economical of manufacture.

How I accomplish the foregoing as well as still further objects and advantages will be made apparent from the following detailed description of a presently preferred adaptation of my invention, for which purpose I shall refer to the accompanying drawing, in which:

Fig. 1 is a perspective showing my device in position with its filling opening closed;

Fig. 2 is a view similar to Fig. 1 but showing the filling opening in open position;

Fig. 3 is a section on line 3—3 of Fig. 1; and Fig. 4 is a section on line 4—4 of Fig. 2.

Referring now more particularly to the drawing, I show this exemplar of my invention as being comprised of a circular body consisting of a side wall member 5. This wall member 5 consists of two companion flexible strips 5a, 5b having their peripheral edges 5c sewed together by stitching 6, 6a and turned inwardly, thus providing a pad-like wall substantially impervious to passage of powder. Strips 5a, 5b are preferably made of a soft, fleecy fabric such as velour. An opposite, flexible dispensing side wall 7, made of a relatively porous fabric having powder passing interstices 7a between its threads, has its peripheral edge secured between the peripheral edges of strips 5a, 5b by the stitching 6, except for a portion shown at the top of Figs. 1 to 4 which is left unstitched to provide a filling opening 10 between wall 7 and body 5. Since wall 7 and body 5 are unsecured together at their medial portions, a powder chamber 11 is provided therebetween, into which powder is poured through opening 10. Wall 7 has an inner lining 9 of a meshed fabric material, such, for instance, as cheesecloth, which is cut coextensive with wall 7 and has its peripheral edge secured between the edges of wall 5 to the same extent and by the same stitching as wall 7, so that in order to be sifted or dispensed through the interstices 7a the powder must first pass through the lining 9. For wall 7, I preferably use a relatively porous, soft velvety material.

For the purpose of effectively closing opening 10 after the filling is completed and for pro-

viding a pocket to receive the fingers of the user whereby to facilitate handling of the puff, I provide a cover member 12 which consists of a flexible, substantially semi-circular fabric strip sewed between walls 5a, 7 at each side of the opening 10 by the stitching 6 and sewed to wall 7 and lining 9 along the edge of the opening 10 by means of stitching 15. This cover 12 is reversible side for side and is sewed between said walls by the stitching 6 a sufficient distance on each side of the opening 10 to cause the cover to be drawn over the face of the puff when the puff is in flattened condition, so that when the cover is in position closing the opening 10 (Figs. 1 and 3), the opening 10 is effectively closed and there is provided a finger-receiving pocket 16 between the cover and the adjacent wall.

Use of the device is as follows: To fill the chamber 11 with powder, the cover 12 is turned from the normal closing position of Figs. 1 and 3, in which position it rests against wall 5a, to reversed or opening position of Figs. 2 and 4, in which position it rests against wall 7. In the latter position the filling opening 10 is exposed to receive the powder. Then the cover is again reversed to the position of Figs. 1 and 3, in which position the opening 10 is effectively closed against escape of the powder therethrough. The powder may be dispensed through wall 7 and lining 9 by patting the outer wall 7 against the skin. Since, before passing through the outer wall 7, the powder must pass through the meshed lining 9, it is more evenly distributed and its flow is so regulated that an undue amount is not dispensed at any one spot. Inasmuch as the peripheral edge of the meshed lining 9 is secured between the peripheral edges of the side walls, the powder cannot escape from the chamber around the peripheral edge of the lining. The wall 5a may be used to further spread the powder on the skin after it is dispensed through wall 7.

While I have resorted to considerable detail for the purpose of making my invention understood, I wish it understood that within its broader scope, as defined by the appended claim, various modifications and adaptations may be made without departing from the spirit of the invention.

I claim:

A refillable powder puff of the class described comprising two superposed fabric sheets secured together along their peripheral edges and providing a powder receiving chamber therebetween, one of the sheets being powder pervious and the other being powder impervious, a meshed fabric member lining the inner face of the pervious sheet, a filling opening between the peripheral edges of the sheets, and a flap providing a cover for the opening.

MYRTLE L. HARLLEE.
